CATHODE-RAY TUBE

David E. Sunstein, Cynwyd, and Arthur H. Mankin, Philadelphia, Pa., assignors, by mesne assignments, to Philco Corporation, Philadelphia, Pa., a corporation of Pennsylvania

Application October 18, 1945, Serial No. 623,114

5 Claims. (Cl. 250—155)

1

Our invention relates to cathode ray tubes and more particularly, to a means for accelerating the electron beam in a cathode ray tube after deflection without decreasing the amount of deflection.

In present cathode ray tubes using post-acceleration, i. e., using acceleration of the electron beam after the deflection of the electron beam, there is introduced a certain amount of distortion and decrease in image size because of the configuration of the electric field used for this post-acceleration. In turn, the configuration of this post-accelerating electric field is controlled by the placing or location of the electrode used for producing this field. In present tubes, this is commonly manifested as a ring around the edge of the tube near the fluorescent screen.

We have discovered that if a radial electric field, centered near the point where the electrons emerge from the deflection system, is provided, the above-stated defects in prior-art devices are overcome.

In one embodiment of our invention, we make the entire fluorescent screen part of the post-accelerating electrode. However, we shape the fluorescent screen so that it will be part of a spherical surface the center of which is in the neighborhood of the deflection means used for the electron beam. In addition, in the neighborhood of the deflection means another electrode is so energized, that between the fluorescent screen and the location of the deflection means there will be a substantially radial electric field which will accelerate the electron beam no matter how it is deflected by the deflecting means and will not tend to force the electron beam back to the center position of the tube as occurs in the present means of post-acceleration.

Thus it is an object of our invention to provide post-acceleration in a cathode ray tube without attendant loss of deflection.

Another object of our invention is the creation of a radial electric field between the deflecting means and the fluorescent screen.

These objects and other objects of our invention will be best understood by reference to the accompanying drawing which illustrates one embodiment and which shows a cross-section of the cathode ray tube and its essential parts.

Referring to the drawing, the envelope of the cathode ray tube 6 is flared out at the end opposite the electron gun 7. This electron gun creates a beam of electrons which progresses axially through the tube towards location 8. In progressing from gun 7 to location 8, the beam is ac-

2

celerated by an electric field existing between the gun 7 and accelerating anode 1. This electric field is produced by a source of electrical potential 11 which keeps anode 1 at a potential higher than the potential of the cathode of electron gun 7. As the electron beam approaches location 8, it is deflected by the deflection yoke 2. As illustrated in this figure, this is a magnetic deflection yoke and may comprise means for the deflection of the electron beam in two mutually perpendicular directions. One of these directions is in the plane of the figure and the other one is in the plane perpendicular to the figure, but still passing through the longitudinal axis of the cathode ray tube.

The fluorescent screen 3, upon which the electron beam eventually impinges, may be formed in a circular or spherical shape with a center at location 8. This fluorescent screen 3 may be bordered by an electrode 4 coated on the inside of the glass or placed inside the tube near the fluorescent screen. This electrode may be a separate and special electrode for aiding in the production of the electric field as will be hereinafter described, or electrode 4 may be subdivided into segments to serve as bordering electrodes, as is described in Patent No. 2,523,162, issued Sept. 19, 1950.

In addition, an external conducting shield may be placed outside of the cathode ray tube to assist in the formation of the electric field. This shield 5 is so located and arranged that it is an effective continuation of the spherical surface formed by fluorescent screen 3 and bordering electrode 4. The geometrical configuration of shield 5 and the potential applied thereto are such as to assist in the formation of the radial field, particularly near the edges of the fluorescent screen. The spherical configuration shown provides this function when the glass was 6 is thin and has negligible electronic charge accumulated thereon. Electrical connection between this shield 5 and the bordering electrode are made by a conductor passing through the glass wall of the cathode ray tube at seal 13. Shield 5, the border electrode 4, and the fluorescent screen are all held at a potential above that of anode 1 by a source of potential 12, which is represented as a battery, but which may be any convenient means of producing such a potential.

It is well known in electrical theory that in arrangements such as shown in Figure 1, namely an electrode in the form of a spherical surface, composed of fluorescent screen 3, bordering elec-

trode 4 and external shield 5, in association with a centrally located electrode such as an accelerating anode 1, will create a radial or substantially radial field between the spherical surface and the central location of anode 1. These electric field lines are indicated by arrows in the figure. Of course, in the immediate vicinity of location 8, the electric field is not radial, but this arises because the field does not emanate from a point charge at location 8, but rather emanates from the end of anode 1 which is nearest to the fluorescent screen. This distortion of the field, however, does not extend for a very great distance beyond location 8 and consequently any distortion in the deflection of the electron beam will not be very great.

Inspection of these radial electric field lines will show that the electron beam after deflection by deflection yoke 2 will be travelling in a direction parallel to the electric field lines. Consequently, the electric field lines will always tend to accelerate the electron in the direction it is moving but will not tend to give a sidewise acceleration to the electron. The result of this is that substantially no extra deflection is imparted to the electron beam. Substantially all of the deflection which has been given to it by yoke 2 is retained as the electron is accelerated by the electric field toward the fluorescent screen.

Under certain circumstances, it may be desirable to cause the fluorescent screen 3 to cover most of the end of the cathode ray tube leaving boundary electrodes 4 as rather narrow strips. Under such a circumstance, an electron beam deflected to its fullest extent might conceivably be subject to a distortion in the electric field except for the presence of shield electrode 5. This shield electrode 5 insures that the edge effect of the electric field will occur well outside of the glass envelope of the cathode ray tube and consequently will cause no distortion of the electric field within the cathode ray tube.

In operation of this post-deflection means, the fluorescent screen 3, electrodes 4 and shield 5 is placed at a potential which is considerably above the potential of anode 1. Thus members 3, 4 and 5 themselves become potential anodes. For example, members 3, 4 and 5 might conveniently be held at +5,000 volts, whereas anode 1 would be held at +1,000 volts both voltages being measured with respect to cathode 7.

In order to assure the proper formation of the electric field in the neighborhood of fluorescent screen 3, it is desirable that the fluorescent screen be somewhat conducting. Thus the phosphor used in its construction may be a conducting phosphor or a very thin coating of metal may be placed over the screen.

By using a high resistance semi-conducting phosphor, the tube can be made flat-faced, or in general, concave or convex depending on the radial resistance pattern and the secondary emission pattern of the phosphor. It can be seen that electrons striking the phosphor will get back to the second anode by conduction, and to a lesser extent by secondary emission, and in so doing they will set up potentials in the phosphor which will maintain the substantially radial field in spite of the non-conformity of the tube face to the isopotential lines.

Our invention causes an additional practical advantage in that secondary electrons emitted from the fluorescent screen immediately encounter, upon their emission, an electric field of large value which tends to force them back

into the fluorescent screen. In such a circumstance, the secondary electrons do not depart far enough from the spot at which the beam impinges to give a significant spreading of the spot. Thus our invention provides a means for post-acceleration of electrons without distortion and without spreading of the beam.

We have described our invention with respect to a specific embodiment thereof, but we prefer to have our invention delineated by the following claims.

We claim:

1. A cathode ray tube comprising an envelope, an electron gun, deflecting means, an accelerating anode, a fluorescent screen, a dome-shaped electrode bordering said screen having its center of curvature substantially at the region of deflection of said deflecting means, and a shield mounted outside said tube and forming an effective continuation of said screen.

2. A cathode ray tube comprising an envelope, an electron gun, deflecting means, an accelerating anode, a fluorescent screen, a dome-shaped electrode bordering said screen having its center of curvature substantially at the region of deflection of said deflecting means, said border electrode and deflecting means being held at a potential above the accelerating anode, and a shield mounted outside said tube and forming an effective continuation of said screen.

3. A cathode ray tube comprising a source of an electron beam, a fluorescent screen, deflecting mechanism between said source and screen for controlling the deflection of the electron over said screen, a post accelerating electrode located beyond said deflecting mechanism with relation to said source and arranged to create a substantially radial electric field from said deflecting mechanism to said screen for accelerating said electrons, said post electrode comprising an electrode bordering said screen, and an external conducting shield forming a continuation of said screen and connected to said bordering electrode, said last mentioned electrode and shield having a positive potential with respect to the portion of said tube adjacent said deflecting mechanism.

4. A cathode ray tube comprising a source of an electron beam, a fluorescent screen, an accelerating electrode and deflecting mechanism between said source and screen for accelerating and controlling the deflection respectively of the electrons of said beam over said screen, means for maintaining said accelerating electrode at a positive potential with respect to said source of electrons, said fluorescent screen comprising a high resistant semi-conducting phosphor and means for maintaining the said phosphor at a substantially high positive potential with respect to the accelerating electrode at the region of the tube adjacent the deflecting mechanism and forming a post accelerating electrode for accelerating the electrons of said electron beam after they have been deflected, the radial resistance pattern of the semi-conducting phosphor screen being of a value to maintain a radial electric field from said screen to said region at said deflecting mechanism.

5. A cathode ray tube comprising a source of an electron beam, a fluorescent screen deflecting mechanism between said source and screen for controlling the deflection of the electrons of said beam over said screen, means for maintaining said region at said deflecting mechanism at a predetermined potential, said fluorescent screen comprising a high resistant semi-conducting

phosphor and being maintained at a positive potential with a respect to the region adjacent the deflecting mechanism, an anode on said fluorescent screen, the electrons striking said phosphor screen, a conductive connection between said phosphor screen and anode, said anode and phosphor screen forming a post accelerating electrode for accelerating the electrons of said electron beam following the deflection of said electron beam, the radial resistance pattern of the semi-conducting phosphor screen being of a value to maintain a radial electric field from said screen to said region at said deflecting mechanism.
